COMBINATION ROASTING AND BAKING OVEN

Richard T. Keating, Oak Park, Ill.

Application July 9, 1959, Serial No. 56,711

Term of patent 14 years

(Cl. D81—4)

I claim:

The ornamental design for a combination roasting and baking oven, as shown.
